GAMEBOARD

Raymond R. Poliakoff, Boonville, Ind.

Application July 29, 1959, Serial No. 56,993

Term of patent 3½ years

(Cl. D34—5)

Fig. 1

Fig. 2

Fig. 1 is a top plan view of a gameboard showing my new design; and

Fig. 2 is an edge view thereof.

The dominant feature of my design resides in the portion shown in full lines.

I claim:

The ornamental design for a gameboard, substantially as shown and described.
